(57) **CLAIM**

The ornamental design for a container with eyelet, as shown and described.

DESCRIPTION

FIG. 1 is a front perspective view of a container with eyelet, according to our design;

FIG. 2 is a rear perspective view thereof;

FIG. 3 is a front view thereof;

FIG. 4 is a back view thereof;

FIG. 5 is a top plan view thereof;

FIG. 6 is a bottom plan view thereof;

FIG. 7 is a left side elevational view thereof; and,

FIG. 8 is a right side elevation view thereof.

In FIG. 6, the broken lines are for the purpose of illustrating portions of the container with eyelet that form no part of the claimed design.
